UNITED STATES PATENT OFFICE.

WILLIAM C. MINTLE, OF LIBERTY, ILLINOIS.

NUT-LOCK.

SPECIFICATION forming part of Letters Patent No. 329,063, dated October 27, 1885.

Application filed July 27, 1885. Serial No. 172,832. (No model.)

To all whom it may concern:

Be it known that I, WILLIAM C. MINTLE, a citizen of the United States, residing at Liberty, in the county of Adams and State of Illinois, 5 have invented a new and useful Improvement in Rail-Joints, of which the following is a specification, reference being had to the accompanying drawings.

My invention relates to improvements in 10 rail-joints for connecting the meeting ends of the rails of a railway-track; and the novelty consists in the construction, combination, and arrangement of the various parts for service, substantially as hereinafter fully set forth, and 15 particularly pointed out in the claim.

The object of my invention is to provide a 20 railway-joint which shall be simple and strong in construction, efficient in operation, and capable of being applied to any ordinary rail.

In the drawings hereto annexed, Figure 1 25 is a side elevation of a railway-track having my invention applied thereto. Fig. 2 is a cross-section in the line $\alpha\alpha$ of Fig. 1, through one of the securing-bolts. Fig. 3 is a detail perspective view of the securing-plate. Figs. 30 4 and 5 are detail views of the securing-bolt and fastening-key.

Like letters of reference indicate like parts in all the figures of the drawings, referring to 35 which—

A A designate the rails of a railway-track of ordinary construction, which meet and abut together at the point a , the web of each rail near the meeting ends thereof having one or 35 more openings or apertures, $a' a'$, for the passage of the fastening or securing-bolts B B.

C C designate fish-plates secured between 40 the head and foot of the meeting ends of the rails A and against the webs thereof, said plates being fitted on opposite sides of the rails and overlapping the ends thereof. The plate C has openings or perforations c of square form, and is adapted to receive the squared portion b of the bolt B, the openings 45 therein registering with the openings in the web of the rail when the plate C is in position against the same. The plate C' is also provided with a number of apertures or 50 openings, c' , corresponding with the number and shape in the web of the rails, with which they register when the plate is in its proper

position. The plates C C' being in proper position against the webs of the rails, and the apertures of said rails and plates coinciding, the bolts B are then passed through the 55 rails and plates, and the nuts or taps b' screwed thereon tightly against the outer face of the fish-plate C', the head of said bolt fitting against the outer face of the plate C, as clearly shown.

D designates a securing or fastening plate of rectangular form, and having apertures or openings $d d$ therein, through which the outer ends of the bolts B pass, said plate fitting closely against the outer face of the fish-plate 65 C'. The apertures or openings in said plate D correspond in number with the bolts employed, and on the inner face the plate is provided with a series of countersinks, $d' d'$, surrounding the openings or apertures, of a 70 shape and size corresponding to the nuts b' , which are adapted to fit snugly and securely therein and be prevented from turning or becoming displaced thereby.

The ends of the bolts B are screw-threaded, as at b^3 , and extend clear through the securing-plate and project slightly beyond the same, and at their outer ends they are provided with openings or apertures b^2 , formed therein, through each of which is passed the 75 arms of a fastening-key, E. The key E comprises a head, e , and two spring-arms, e' , which spread or spring apart at their lower ends when in position in the bolt, and are thus prevented from being displaced, said key 80 bearing against the face of the plate and serving to retain it in position and from becoming 85 misplaced.

I have shown but four bolts and their nuts and keys, two being arranged on each side of 90 the line where the rails meet; but it is obvious that the number may be varied, and other details in construction may be made without departing from the principle or sacrificing the advantages of my invention, the 95 essential features of which will be readily understood from the foregoing description, taken in connection with the drawings.

It will be observed that the nuts b' are housed within, wholly or partially, the securing-plate D, and are thereby shielded from 100 the action of the weather, and, further, that

they are prevented from turning or becoming detached by the jars and shocks incident to the passing of a train over the rail.

A joint constructed in accordance with my invention is cheap, simple, and strong and efficient in service, and may be readily detached from and applied to an ordinary rail-way-track.

Having thus fully described my invention, what I claim as new, and desire to secure by Letters Patent, is—

In a rail-joint, the combination, with the rails A A, of the apertured fish-plates C C', adapted to overlap said rails, a securing-plate, D, having openings d and countersunk portions d' on its inner surface, bolts B, passing through

fish and securing plates and the rails, nuts b', fitted on said bolts and housed within the countersunk portion of the plate D, and spring fastening-keys E, passing through an opening in each bolt and bearing against the face of the plate D, all arranged and adapted to serve substantially as and for the purpose herein described.

In testimony that I claim the foregoing as my own I have hereto affixed my signature in presence of two witnesses.

WILLIAM C. MINTLE.
